United States Patent Office

Des. 200,917
Patented Apr. 20, 1965

200,917

SKATE BOARD

Bill Markham, 7257 Pacific View Drive,
Los Angeles, Calif.

Filed Aug. 19, 1964, Ser. No. 81,363

Term of patent 14 years

(Cl. D34—15)

FIG. 1.

FIG. 2.

FIG. 3.

FIG. 4.

FIGURE 1 is a perspective view of a skate board showing my new design;

FIGURE 2 is a top plan view of the skate board of FIGURE 1;

FIGURE 3 is an enlarged fragmentary side elevational view thereof; and

FIGURE 4 is a bottom plan view of the skate board.

I claim:

The ornamental design for a skate board, as shown.

References Cited by the Examiner

UNITED STATES PATENTS

1,056,357 3/13 Murdock ----- 280—87.04

EDWIN H. HUNTER, Primary Examiner.